DESIGN FOR A RADIATOR CAP

Albert T. Sebek, Cicero, Ill.

Application March 26, 1934, Serial No. 51,190

Term of patent 3½ years

To all whom it may concern:

Be it known that I, ALBERT T. SEBEK, a citizen of the United States, residing at 2303 South 62nd Avenue, Cicero, Cook County, Illinois, have invented a new, original, and ornamental Design for a Radiator Cap, of which the following is a specification, reference being had to the accompanying drawing, forming part thereof:

Fig. 1 is a front elevation of a radiator cap embodying my new and ornamental design;

Fig. 2 is a plan view of same, and

Fig. 3 is a side view of same.

I claim:

The ornamental design for a radiator cap as shown.

ALBERT T. SEBEK.
